JOHN MAXWELL COOTE, OF ELIZABETH, NEW JERSEY.

RENEWABLE KNIFE-BLADE FUSE.

1,308,000.

Specification of Letters Patent. Patented June 24, 1919.

Application filed December 31, 1917. Serial No. 209,650.

To all whom it may concern:

Be it known that I, JOHN MAXWELL COOTE, a citizen of the United States, and a resident of Elizabeth, in the county of Union and 5 State of New Jersey, have invented certain new and useful Improvements in Renewable Knife-Blade Fuses, of which the following is a specification.

The invention relates to improvements in 10 electrical fuses, more particularly of the knife-blade type wherein a fusible wire or link is held within a suitable shell or protecting covering by means of a carrier having two protruding contact blades, said carrier being suitably secured to the shell. The present invention has for its object to provide a fuse of this character wherein the 15 said fusible element may be inexpensively and readily replaced in case the same is blown by excessive current, and to provide a substantial construction of few and simple parts whereby rigidity of the contact blades will be insured.

The nature of the invention will be best 20 understood when described in connection with the accompanying drawings, in which—

Figure 1 illustrates the improved knife-blade fuse in elevation.

Fig. 2 is a horizontal section therethrough. Fig. 3 is an end view with cap removed. Fig. 4 is an elevation of the inclosing shell.

Fig. 5 is an elevation of the fuse and of 35 the contact elements constituting the carrier therefor, the inclosing shell and caps being removed.

Fig. 6 is a plan of the locking member or washer.

Fig. 7 is a section taken on the line 7—7, Fig. 6.

Fig. 8 is a section taken on the line 8—8, Fig. 5.

Similar characters of reference designate 45 corresponding parts throughout the several views.

Referring to the drawings, 10 designates the inclosing shell usually tubular in form and of insulating material, the same being 50 exteriorly threaded at each end to receive caps or ferrules 11 and 12 which assist in retaining the fuse carrier to the said shell.

This carrier comprises two thin strips or 55 blades 13 and 14 provided with intermediate flanges or thin disks 15 and 16 having vents 17 to permit of the escape of the gases re-

sulting from the blowing of the fuse. The disk 15 is provided with a shoulder 18 of sufficient diameter to abut the one end of the shell 10, thus preventing the carrier from 60 being drawn therethrough; and, to insure against rotational movement of the said carrier with reference to the shell, diametrically-disposed lugs 19, for example in the plane of the blade, extend inwardly from 65 said shoulder and fit corresponding notches 20 of the particular end of said shell. The cap 11 for this end of the shell fits over the disk 15 and has an inwardly-directed circular flange 21 which serves to coat with said 70 disk to hold the same firmly to the end of the shell 10.

The other disk 16 is of lesser diameter than the internal diameter of said shell in order to permit the carrier to be forced 75 through the shell when the said carrier is assembled, as shown in Fig. 5 of the drawings, that is to say, when the fusible link or wire 22 is secured in position at the inner ends of the blades 13 and 14. These links 80 are of predetermined length, preferably of round wire with flattened terminals, and are held to the inner ends of the blades by suitable means, for example bolts 23 and nuts 24 with suitable washers 25 interposed. 85 This fuse unit, comprising the blades 13 and 14 held in spaced relationship by the link, may thus be handled as a whole and be inserted into the shell 10 and retained at the one end 13, as aforesaid. If desired, a suitable filler (not shown), such as asbestos or lime, may surround the said link.

To locate the other blade end 14 and insure rigidity of same with reference to the shell 10, the disk 16 thereof is caused to be 95 displaced a predetermined distance with reference to the corresponding end of the shell 10. A washer or locking member 26, provided with a diametral slot 27 extending from one end substantially through the said 100 washer, is arranged, furthermore, to be fitted by means of said slot over the inner portion of the blade 14 and between the disk 16 and the corresponding end of the shell 10. This washer is provided with vents 28 105 registering with, when the washer is in locking position, the corresponding vents of the disk 16. The said washer, moreover, in order to prevent rotational movement of the shell 10 relatively thereto, is provided with 110 a lug 29 directed inwardly from its circumference and fitting a corresponding notch 30

of the end of the shell. This lug is located preferably at the closed end of the slot, and at the other open end thereof further lugs 31 are directed downwardly from the sides 5 of the slot to coat with the opposite sides 32 of a notch 33 of the end of said shell. The washer is thus fixed with respect not only to the blade 14, but also with reference to the shell 10, whereby rigidity of the various parts is insured. To further insure 10 this rigidity and to present a finished appearance to the fuse, the disk 16, which is preferably in the form of a truncated cone, is designed to coat with the inwardly-projecting flange 34 of the cap 12 which is correspondingly tapered on its inner face so that, when the same is screwed down over 15 the end of the shell 10, the parts are further bound and held in place.

20 I claim:

1. A renewable knife-blade fuse, comprising: two oppositely-disposed blade contact members; a fusible element secured to same; a shell inclosing said fusible element and 25 portions of said blade contact members; a member slotted to receive one of the blade contact members to aline same and secure both to the shell; and caps fitting over the blade contact members and ends of said shell.

30 2. A renewable knife-blade fuse, comprising: two oppositely-disposed blade contact members; a fusible element secured to same; a shell inclosing said fusible element and portions of said blade contact members, said shell being notched at one end; a removable disk slotted to receive one of the blade contact members to aline the same and secure both to the shell, said disk having lugs fitting the said notches to prevent rotational 35 movement between said shell and blade contact members; and caps fitting over the blade contact members and ends of said shell.

3. A renewable knife-blade fuse, comprising: two oppositely-disposed blade contact members provided with integral flanges intermediate their ends, one flange being of greater diameter than the other; a fusible element secured to said contact members; an inclosing shell through which the flange of 45 lesser diameter is adapted to pass, the flange of greater diameter abutting an end of said shell; and removable means inserted between the flange of lesser diameter and the other end of the shell to lock the contact members 50 to the shell.

4. A renewable knife-blade fuse, comprising: two oppositely-disposed blade contact members provided with integral flanges intermediate their ends, said flanges having 60 suitable vents, and one flange being of greater diameter than the other; a fusible element secured to said contact members; an inclosing shell through which the flange of lesser diameter is adapted to pass, the flange of greater diameter abutting an end 65 of said shell; and removable means inserted between the flange of lesser diameter and the other end of the shell to lock the contact members to the shell, and provided with vents registering with the vents of the flange of lesser diameter.

of said shell; and removable means inserted between the flange of lesser diameter and the other end of the shell to lock the contact members to the shell.

5. A renewable knife-blade fuse, comprising: two oppositely-disposed blade contact members provided with integral flanges intermediate their ends, one flange being of greater diameter than the other; a fusible element secured to said contact members; an inclosing shell through which the flange of lesser diameter is adapted to pass, the flange of greater diameter abutting an end of said shell; removable means inserted between the flange of lesser diameter and the other end 80 of the shell to lock the contact members to the shell; and caps fitting over the blade contact members and the ends of said shell and further securing the contact members to the shell.

85

6. A renewable knife-blade fuse, comprising: two oppositely-disposed blade contact members provided with integral flanges intermediate their ends, one flange being of greater diameter than the other; a fusible 90 element secured to said contact members; an inclosing shell through which the flange of lesser diameter is adapted to pass, the flange of greater diameter abutting an end of said shell; and a circular disk member fitted between the flange of lesser diameter and the corresponding end of the shell to lock the contact members to the shell.

95

7. A renewable knife-blade fuse, comprising: two oppositely-disposed blade contact members provided with integral flanges intermediate their ends, one flange being of greater diameter than the other; a fusible element secured to said contact members; an inclosing shell through which the flange of lesser diameter is adapted to pass, the flange of greater diameter abutting an end of said shell; and a circular disk member fitted between the flange of lesser diameter and the corresponding end of the shell to lock the 100 contact members to the shell, said disk member being provided with a diametral slot extending inwardly from the circumference to receive the corresponding contact blade.

105

8. A renewable knife-blade fuse, comprising: two oppositely-disposed blade contact members provided with integral flanges intermediate their ends, said flanges having suitable vents, and one flange being of greater diameter than the other; a fusible 110 element secured to said contact members; an inclosing shell through which the flange of lesser diameter is adapted to pass, the flange of greater diameter abutting an end of said shell; and removable means inserted 115 between the flange of lesser diameter and the other end of the shell to lock the contact members to the shell, and provided with vents registering with the vents of the flange of lesser diameter.

120

125

130

9. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell; and a circular disk member fitted between the flange of lesser diameter and the corresponding end of the shell to lock the contact members to the shell, said disk member being provided with a diametral slot extending inwardly from the circumference to receive the corresponding contact blade, and with inwardly-extending lugs fitting the notches of the corresponding end of the shell. 35
10. 10. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell; and a circular disk member fitted between the flange of lesser diameter and the corresponding end of the shell to lock the contact members to the shell, said disk member being provided with a diametral slot extending inwardly from the circumference to receive the corresponding contact blade, and with inwardly-extending lugs fitting the notches of the corresponding end of the shell. 40
15. 15. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell, and having inwardly-extending lugs fitting the corresponding notches provided in the end of the shell; and removable means inserted 45 between the flange of lesser diameter and the other end of the shell to lock the contact members to the shell. 50
20. 20. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell; and a circular disk member fitted between the flange of lesser diameter and the corresponding end of the shell to lock the contact members to the shell, said disk member being provided with a diametral slot extending in- 55
25. 25. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell, and having inwardly-extending lugs fitting the corresponding notches provided in the end of the shell; and removable means inserted 60 between the flange of lesser diameter and the other end of the shell to lock the contact members to the shell. 65
30. 30. A renewable knife-blade fuse, comprising: two oppositely-disposed blade contact members provided with integral flanges intermediate their ends, one flange being of greater diameter than the other; a fusible element secured to said contact members; an inclosing shell notched at one end and through which the flange of lesser diameter is adapted to pass, the flange of greater diameter abutting an end of said shell; and a circular disk member fitted between the flange of lesser diameter and the corresponding end of the shell to lock the contact members to the shell, said disk member being provided with a diametral slot extending in-

Signed at New York, in the county of New York and State of New York, this 27th day of December, A. D. 1917.
